Fig. 5.

Fig. 6.

This technical drawing illustrates a mechanical assembly, likely a component of a larger machine. The central feature is a vertical cylinder or piston assembly labeled 64, which is connected to a rod 63. A lever system is attached to the rod 63, with components labeled 61, 66, and 69. A rectangular frame or housing contains this mechanism. A vertical rod 68 extends downwards from the assembly. A circular component, possibly a seal or bearing, is labeled 50 and is associated with a housing labeled 51. A vertical tube or pipe 58 is connected to the assembly. A curved pipe 74 is attached to a valve or fitting labeled 73. A spring mechanism is located on the right side, featuring a coiled spring 48, a lever 47, and a base 49. The entire assembly is mounted within a housing with a hatched pattern. A small circular logo or seal is visible near the bottom center of the drawing.

UNITED STATES PATENT OFFICE

WILLIAM F. HERTING AND FRANK C. CHLAN, OF BALTIMORE, MARYLAND.

SAFETY-SIGNAL SYSTEM FOR RAILWAYS.

No. 875,911.

Specification of Letters Patent.

Patented Jan. 7, 1908.

Application filed April 20, 1907. Serial No. 369,345.

To all whom it may concern:

Be it known that we, WILLIAM F. HERTING and FRANK C. CHLAN, citizens of the United States, residing at Baltimore, in the county of Baltimore City and State of Maryland, have invented certain new and useful Improvements in Safety-Signal Systems for Railways, of which the following is a specification.

16 Our invention relates to a safety signal system for railways, and more particularly to a block signal system comprising means for unfailingly signaling a passing train from each block house when it is desired to prevent the train from entering the next block.

Broadly our invention consists in the arrangement at certain points of block houses, electrical contacts arranged at a point distant therefrom and adapted to be operated 20 by an oncoming train to close a circuit and notify the block signal operator.

Furthermore it consists in the arrangement of two magazine torpedo setting mechanisms at points between said block house 25 and said contacts, each of said mechanisms being adapted to be actuated by the operator to place a torpedo upon the track, an annunciator arranged within the block house and electrical mechanism for registering thereon 30 the actuation of said contacts and the movements of said torpedo setting mechanisms and means for automatically returning said torpedo setting mechanisms to receive a new torpedo from the magazine after actuation 35 and release by the operator.

Still further our invention consists in utilizing the torpedo setting mechanism most distant from the block house as the main signal and the nearest one as a reserve in 40 case the first named mechanism fails to properly operate, or in case the engineer on the train disregards the same, and in placing a third and last expedient on the track near the block house in the form of a pivoted lever 45 which may be thrown to the vertical position by the operator, and which will strike a depending lever carried by the engine and will operate said lever to accomplish the closing of a circuit to ring a bell and the showing of a 50 red light in the engine cab, at the same time releasing the air and applying the brakes.

Our invention still further consists in the construction, arrangement and operation of parts as hereinafter described with reference 55 to the accompanying drawings, in which like

figures represent like parts in the several figures and in which,

Figure 1 is a plan view of our improved apparatus showing a complete block. Fig. 2 is an elevation of the annunciator within the block house. Fig. 3 is a side elevation of the cab signal levers that portion carried by the engine being shown in diagram. Fig. 4 is a vertical sectional view through one end of the torpedo setting or placing mechanisms. 65 Fig. 5 is a sectional view on the line 5—5 of Fig. 4 and looking in the direction of the arrows, and Fig. 6 is a sectional view on the line 6—6 of Fig. 5 looking in the direction of the arrows.

Referring to Fig. 1, wherein is shown in practical application our complete safety system, A represents the railroad track having a switch B leading thereon. Block stations 10 and 11 are placed at suitable intervals along the road, one signal block, designated as block 2, being shown in this figure. Block station 10 has electrically connected therewith the contact piece 12 which is arranged beside the track to be depressed by 75 the flange of the engine wheel to complete a circuit through the wires 13 when a train approaches said station in the direction of arrow 6. As the contact shoe is carried on the right side of the engine there will be no contact at the point 12 when the engine moves in the direction of arrow 5. When warned of the approach of a train which the operator at block station 10 must not admit within 80 the next station he will at once pull a rope 85 14 which operates a torpedo setting mechanism arranged at 15, and termed the main mechanism, to place a torpedo upon the rail, and at the same time to actuate a target 16 to show "danger". Should the main tor- 90

pedo mechanism 15 fail to stop the train, the operator will pull a rope 17 which operates the reserve torpedo setting mechanism 18 to place a torpedo upon the rail and to actuate a target 19 to show "danger". Should both 100 the main and reserve torpedo placing mechanisms and the targets be disregarded by the oncoming train, the operator at block station 10 is provided with a third and last expedient in the form of a pivoted lever 20 arranged 105 along the right hand rail and which the operator may actuate to a vertical position by means of a rope 21. When in the vertical position the lever 20 will strike a lever mechanism carried on the right side of the engine, 110

said lever mechanism when struck being adapted to ring a bell and show a red light within the cab of the engine, as will be hereinafter described.

- 5 Should an engine and train approach the block station 11 in the direction indicated by the arrow 5, it will, by means of the contact shoe carried on the right side of the engine, signal the operator through the contact 22 and the circuit wires 23 of its approach. Should the operator be ordered to hold the train, he will first operate his main torpedo placing mechanism 24, by means of the lever 25, to place a torpedo on the rail and actuate 10 its target 26 to show danger. Should this fail he has his reserve torpedo placing mechanism 27, its operating rope 28 and target 29, and should this also fail, a pivoted lever 30 is provided, similar to the lever 20, operated by a rope 31 to actuate signals within 15 the cab of the engine.

Although we have shown and described the operating elements for the several mechanisms as ropes, it will be understood that in 25 the practical usage of our invention, levers will be employed with bell-cranks connecting them.

We will now describe the torpedo placing mechanism, it being understood that each of 30 said mechanisms are alike in construction and operation. A casing 32 is provided with a two-part cover or lid, the portion 33 thereof being rigidly secured to the casing by means of bolts 34, and having a shoulder 35 formed thereon, and the portion 36 having a groove 37 fitting below and about the shoulder 35 and locked to the casing 32 at 38. Vertically arranged from its bearing 39 in 35 the casing 32 is a rotatable shaft 40 mounted 40 through the supporting frame 41, bolted to the base of said casing. The shaft 40 is provided with a toothed segment 42 and a chain 43 connected thereto, which is adapted to be operated by a rope or cable 44 from the block 45 station to partially rotate said shaft 40. A swinging torpedo placing arm 45 is thus 50 swung from the torpedo magazine 46 to the car rail through the door 47 which is automatically opened for the passage of said arm 45 through the casing 32 by means of a spring 48 attached to an overhanging stop frame 49 and to said door. When, however, the mechanism is released by the operator at the block station a spring 50, stronger than 55 spring 48, and arranged between the segment 42 and arm 51 of the frame 41 will pull said swinging arm back to its normal position and will further pull said door 47 closed by means of the loose chain connection 52 60 arranged between said door and the swinging arm 45.

Mounted on the upper end of shaft 40 to rotate therewith and extending through a bearing 53 in the position 33 of the cover is a 65 signal shaft 54 having a target 55 and a sig-

nal lamp 56 on the upper end thereof and so arranged that a red or danger signal will show along the rails when the mechanism is operated to place a torpedo.

Within the magazine 46 are adapted to be 70 arranged a plurality of torpedoes 57 each provided with an extending tongue 58 adapted to be grasped between the upper and lower jaws 59 and 60 respectively arranged on the end of the swinging arm 45 and pivoted at 75 61. A leaf spring 62 bearing upwardly against the under face of the rearwardly extending portion of jaw 59 beyond its point of pivot, serves to close said jaws upon the torpedo while a U-shaped rod frame 63 pivoted 80 in and depending from the supports 64 and arranged to engage the upper surface of said extending position of said jaw 59 serves to open said jaws slightly to grasp the torpedo.

In order to feed the torpedoes down to be 85 grasped one at a time I provide a pair of fingers 65 and 66, said finger 66 being arranged to enter the magazine a distance above said finger 65 equal to the thickness of one torpedo. The fingers 65 and 66 are pivotally 90 mounted adjacent the opposite ends of an oscillating member 67 pivoted centrally to the arm 68 of the frame 41. An operating rod 69 is connected to said member 67 by means of a universal joint 70 and is provided 95 with an adjustable bracket 71 which is arranged to be struck by the arm 45 to oscillate said member 67 and thrust said finger 66 within the magazine 46 below the torpedoes. When the mechanism is operated to place a 100 torpedo upon the rail, and the arm 45 thereby swung outward, a spring 72 will operate to withdraw the upper finger 66 and insert the lower finger 65 which will then support the torpedoes until the arm 45 is again re- 105 turned when said finger will be withdrawn to drop a torpedo to be clasped by the jaws 59 and 60 and the finger 66 again inserted to prevent more than one torpedo dropping.

Should the torpedo, after having been 110 placed on the rail, be not exploded the said torpedo will therefore return within the casing 32 in the grasp of the swinging arm 45, and will strike the curved end 73 of the operating rod 69 thus lifting said rod upward on 115 its universal pivot 70 and allowing said arm 45 to pass under the bracket 71 without actuating the oscillating member 67. The torpedo will at the same time strike the curved lower arm 74 of the rod 75, in the form of a 120 bell-crank-lever, pivoted at 76 to an arm 77 of the frame 41 and connected at its other end to the rod frame 63. When thus struck by the torpedo said bell-crank-lever operates to throw said frame 63 out of contact with 125 the extension of the jaw 59 and thus prevent the opening of the jaws.

An annunciator such as we have shown in Fig. 2, is designated to be used within each block station, the one shown being marked 130

especially for block station 10. The annunciator board 78 is divided in half, each half indicating the actions taking place in the blocks on both sides of the station, and under 5 the control of the operator. I will describe the half marked "Block #2." with reference to Fig. 1 which shows the scheme of this block and Fig. 5, which shows the wiring within the torpedo placing mechanism. The 10 negative wires 79 and 79^a leading from the main mechanism indicator 80 and also from the reserve mechanism indicator 81, are connected within their respective casings to the curved insulated strips 82 and 83 respectively while the positive current carrying wire 84 from the annunciator which has a battery 85 arranged in circuit therewith, is connected to the rearwardly extending shank 86 of the swinging torpedo placing arm 45. 15 Thus when said arm 45 is actuated to place a torpedo the shank 86 will be moved to contact with strip 83 thus closing a circuit through wire 79^a to actuate the indicator to register "on". As the torpedo placing mechanism is released the shank 86 will contact with the strip 82 and will complete a circuit through the wire 79 to actuate the indicator to register "off". The actuation of the indicators 87 will be through the wires 13 as previously 20 described.

The last expedient by which the operator may hope to stop the train is by means of a pivoted lever shown at 20 and 30 in Fig. 1, in connection with stations 10 and 11 respectively and illustrated in detail, together with the mechanism carried on the engine, in Fig. 3. In this figure the lever 88 is pivoted in the frame 89, secured along side of the rail to drop to a horizontal position by gravity. A 25 stop 90 limits the movement of the lever 88 to the vertical position under the actuation of the rod 91 connected to the lever 88 by means of the coil spring 92. The engine mechanism comprises a bell-crank lever 93 adapted to be operated by the lever 88 the shock of contact between said levers being absorbed by means of the contact shoes 94 and said coil spring 92. Arranged vertically on the engine is an operating rod 95 terminating at its lower end in an enlarged chamber 96 within which is disposed the enlarged head 97 of a connecting rod 98 pivoted to the horizontal arm of the bell-crank lever 93. Mounted preferably within or adjacent the 30 engine cab, and in full view of the engineer is a shutter 99 sliding in a frame 100 and provided with a transparent red window 101. The upper end of the rod 95 is normally pressed upward by means of the spring 102 into locking engagement with the catch 103 mounted on the shutter 99 by which said shutter is held from displacement. When the lever 93 strikes the lever 88 the rod 95 will be depressed, thus releasing the shutter 35 99 and allowing the same to slide along the

frame 100 under the actuation of springs 104 until the contact shoe 105 carried by said shutter contacts with the pieces 106, thus completing a circuit through the wires 107 and battery 108 to ring a bell 109, and attract the attention of the engineer. A lamp 110 is suitably arranged to shine through the window 101 and thus show a red light. We also preferably employ such connections with said lever mechanism as will readily and automatically release the air and set the brakes, upon the actuation of the same. 70 75

It will be seen that if the engine passes backward over the lever 88 there will be no actuation of mechanism as just described, 80 by reason of the sliding connection 96 and 97 between the operating rod 95 and the connecting rod 98.

Having thus fully described our invention, we claim:

1. In a block signal system for railroads, the combination with the block stations, of means for signaling the approach of a train therein, main and reserve torpedo setting mechanisms disposed alongside the rails and 90 operable from said stations, and engine signal actuating members arranged to be moved to the operative position from their respective stations, substantially as described. 85 95

2. In a block signal system for railroads 95 the combination with the block station of means for signaling the approach of a train therein, main and reserve torpedo setting mechanisms disposed at intervals along the road, means for actuating said mechanisms 100 from their respective stations to place a torpedo, and means for registering such actuation within said stations, substantially as described.

3. In a block signal system for railroads 105 the combination with the block station of means for signaling the approach of a train therein, main and reserve torpedo setting mechanisms disposed at intervals along the road, means for actuating said mechanisms 110 from their respective stations to place a torpedo, and engine signal actuating members arranged to be moved to the operative position from their respective stations, substantially as described. 115

4. In a block signal system for railroads the combination with the block stations of means for signaling the approach of a train therein, main and reserve torpedo setting mechanisms disposed at intervals along the 120 road, means for actuating said mechanism from their respective stations to place a torpedo, means for registering such actuation within said stations, substantially as described. 125

5. In an engine signal for railway block systems, the combination with a lever mounted alongside the rail and operable from the block stations of a lever mechanism carried by the engine and actuated by said 130

lever, a sliding shutter releasable upon the actuation of said mechanism, an alarm bell mounted within the engine cab, a pair of spaced contacts electrically connected to said bell, and a contact shoe carried by said shutter and adapted to complete a circuit through said contacts upon the release of said shutter, substantially as described.

6. In an engine signal for railway block systems, the combination with a lever mounted alongside the rail and operable from the block station of a lever mechanism carried by the engine and actuated by said lever, a sliding shutter releasable upon the actuation of said mechanism and provided with a transparent section and alarm bell mounted within the engine cab, a pair of spaced contacts electrically connected to said bell a contact shoe carried by said shutter and adapted to complete a circuit through said contacts upon the release of said shutter, and a lamp mounted to reflect through said transparent section when said shutter is released, substantially as described.

7. In a torpedo placing mechanism, the combination of a rotatable shaft and means for rotating the same a swinging arm mounted thereon and provided with pivoted clasping jaws on the end thereof, a magazine car-

rying a plurality of torpedoes, means for automatically opening said jaws to clasp a torpedo, and means for preventing the actuation of said jaw opening mechanism should said arm be returned with an unexploded torpedo, substantially as described.

8. In a torpedo placing mechanism the combination of a rotatable shaft and means for rotating the same, a swinging arm mounted thereon and adapted to be actuated by the rotation thereof to place a torpedo, a torpedo magazine, mechanism for feeding the torpedoes downwardly therein one by one, a pair of pivoted torpedo clasping jaws arranged at the end of said arm, means for returning said arm to the normal position after actuation, mechanism for opening said jaws to clasp a torpedo, and means for preventing the actuation of said feeding mechanism and said jaw opening mechanism should said swinging arm be returned with an unexploded torpedo, substantially as described.

In testimony whereof we affix our signatures in presence of two witnesses.
